MARION MALLORY, OF TOLEDO, OHIO.

IGNITION SYSTEM.

Application filed February 6, 1928. Serial No. 252,414.

My invention has for its object to provide a means whereby the resistance of the primary circuit of an ignition system will be varied according to two changeable factors occurring in the primary circuit, one of which is the quantity of current that flows through the primary of the induction coil of the system, and the other is the length of time in which the altered current flows in said circuit. Thus, by my invention, I have provided a means for reducing the quantity of current through the primary of the induction coil of the ignition system as the system rises in temperature and becomes more efficient in the performance of its functions. When the engine, in connection with which the system is used, becomes "warmed up", the quantity of current required for the efficient operation may be considerably reduced. To control the variation and give opportunity for the apparatus to respond efficiently to such variation, my invention provides a means for delaying such change until the ignition system and the engine are in condition to operate efficiently under such changed condition.

Thus the invention provides a resistance that is located in series with the primary coil of an ignition system and a thermic means that is heated by the flow of current in the primary circuit and is so connected with the resistance as to reduce the current flow through the primary coil and the thermic device. If the current is relatively large and is maintained a sufficient period of time to heat the thermic device, the thermic device operates to cause an increase in the resistance of the primary circuit to reduce the flow of the current through the coil, and reduce the temperature actuating the thermic device until the flow of the current and the temperature of the thermic device are substantially constant while the average operation of the engine is constant or substantially uniform. Thus, by my invention, opportunity is given for continued operation of the ignition system under substantially the initial conditions of the starting of the operation of the engine until there has been full opportunity for the engine to become "warmed up" and then, as the temperature of the thermic device rises, it re-

quires a lapse of time during which there is but a slight increase of resistance in the circuit, and, upon expiration of a period having a length sufficient to assure continued operation of the engine, the resistance in the primary circuit is increased by the movement of the thermic device to a relatively high value at which it is kept until for a period of time the engine alters its average speed or condition of operation.

The invention may be contained in systems that vary in their details, and, to illustrate a practical application of the invention, I have selected two or three forms of devices for controlling the flow of current in the primary coil of an ignition system.

Fig. 1 illustrates one form of construction wherein the resistance of an ignition system may be thermically controlled. Fig. 2 illustrates the connection of the parts of the system in which the device illustrated in Fig. 1 is connected. Fig. 3 illustrates another form of construction for thermically controlling the resistance of the primary circuit and of the ignition system. Fig. 4 is a diagram of the system in which the device, illustrated in Fig. 3, is connected. Fig. 5 illustrates a modified form of thermic controlling device. Fig. 6 illustrates a system in which the device illustrated in Fig. 5 is connected. Fig. 7 illustrates a further form of thermic device embodying my invention. Fig. 8 illustrates a longitudinal section of a modified thermic device embodying my invention. Fig. 9 indicates diagrammatically the connections of the device illustrated in Fig. 7. Fig. 10 indicates diagrammatically the connections of the device illustrated in Fig. 8, with the ignition system.

In the form of construction shown in Figs. 1 and 2, a flexible bi-metal thermic element 1 may be suitably supported on a base and surrounded by a resistance element 2 for heating the flexible bi-metal thermic element 1, according to the flow of current through the resistance element 2. The bi-metal element 1 may be insulated from the resistance element 2 by an insulating flexible sheath, or sleeve, 7. One end of the bi-metal element 1 may be secured to a suitable base by a bracket 3, while the opposite end of the bi-

metal thermic element 1 is provided with a contact 4. The resistance wire, or element, 2, not only surrounds the bi-metal element 1, but also is connected to the contact 4. The contact 4 is insulatingly supported on the free end of the bi-metal thermic element 1 and is located in position so as to make contact with the consecutive turns of a resistance wire 5, preferably mounted on an arcuate insulating block 6. The resistance and movable contact forms a rheostat for varying the flow of current. As the bi-metal thermic element 1 is heated by the wire 2, the bi-metal element 1 is bowed in a direction opposite to its normal or cold position, according to the quantity of heat that is transmitted from the resistance element 2 to the bi-metal element 1. Thus, as the flow of the current through the resistance element 2 is increased, and after the expiration of sufficient time to permit the transmission of the heat from the resistance element 1 to the bi-metal thermic element 1, the bi-metal thermic element 1 will bow so as to vary the amount of resistance in the circuit of the primary coil.

The resistance 5 is connected in series with the primary coil 10 of the induction coil 11. The circuit of the primary coil 10 is opened and closed by means of the circuit closer 12, which is operated by the cam 13 that is located on the cam shaft 14 of the engine, that is controlled by the ignition system in the manner well known in the art. The battery 15 may be connected to the circuit closer 12 and the circuit is completed through the ground to the resistance element 2 of the thermic device. During the continued operations of the circuit closer 12, the quantity of the current will vary according to the length of periods in which the circuit is closed and the rate of the opening and closing of the circuit, which will vary the rate of flow or the quantity of current through the primary circuit, and, to reduce this quantity after it has been allowed to flow for a desired period of time, the thermic device 1 becomes heated and the amount of current through the primary circuit is cut down by movement of the contact 4 over the resistance 5.

In the form of construction shown in Figs. 3 and 4, the thermic element is formed of a pair of sinuous members that are sharply curved and the joint operations of the sharply curved portions operate to extend the length of the sinuous thermic member. As shown in Fig. 4, the sinuous thermic element 20 is supported on a bracket 21 and is surrounded by a heat insulating sleeve 22. A resistance wire 23 is located within the sleeve 22 and is connected at one end to a suitable binding post 24 and at the other end to a contact 25 located in contact with the arm 26. The arm 26 is pivotally sup-

ported by a suitable means and has a contact 27 located at its outer end. The contact 27 is located in position to make contact with the turns of the resistance wire 28 that may be located on an arcuate insulating block 29. As the sinuous thermic element 20 increases in its length, the arm 26 is swung on its pivot point 30 and the contact 27 is moved over the resistance 28. The resistance 28 is connected in the primary circuit of the system illustrated in Fig. 4 and so as to increase the resistance of the circuit. As shown in Fig. 4, the resistance 28 is connected to the primary coil 10 of the induction coil 11 and is in series with, not only the primary coil 10, but also the circuit closer 12 and the battery 15. Thus, as the flow of current increases, an opportunity is given for the heating of the thermic element 20, the resistance of the circuit is increased which operates to reduce the quantity of current that passes through the primary coil 10.

In the form of construction shown in Fig. 5, a mechanical bellows 35 is provided with a pair of binding posts 36 and 37 located, respectively, in the upper and lower heads of the mechanical bellows 35, and a heat coil 38 is located within the mechanical bellows 35 and is connected to the binding posts 36 and 37. The interior of the mechanical bellows 35 may be filled with a suitable gas, or vapor, which will cause the expansion of the mechanical bellows 35 upon a slight variation of the heat of the coil 38. The construction shown in Fig. 5 will thus produce a more prompt response to the change in temperature that may be created by the heat element 38 of the system. One end, or head, of the mechanical bellows 35 is fixedly supported while the other end of the mechanical bellows 35 is connected by a suitable stirrup, such as the stirrup 39, to an arm 40 that may be pivotally secured to a fixed support. The arm 40 terminates in the contact 41 which is adapted to make contact with the turns of the resistance wire 42 that may be located on the arcuate insulating block 43. Consequently, as the mechanical bellows 35 is extended, by the rise of the temperature of the gas or vapor confined within the bellows 35, the arm 40 is moved angularly so as to vary the amount of resistance in the primary circuit of the ignition system. The binding post 36 is connected by means of a flexible wire 43 to the arm 40 and thus the circuit may be completed from the battery 15 to the heat coil 38, the arm 40 and the resistance 42. The resistance 42 is located in series with the primary coil 10 of the induction coil 11 and with the circuit closer 12. Thus, after the flow of current has been maintained, a certain period of time, the mechanical bellows 35 will respond to the change of temperature, produced by the heat coil 38, and increase

the length or the number of turns of the resistance wire 42, which is located intermediate the contact 41 and the point of connection of the resistance wire 42 with the primary coil 10, and thereby the flow of current through the primary coil 10 will be reduced.

In the form of construction shown in Fig. 7, the bi-metal thermic element 45 is located in a sleeve or capsule 46 of insulating material. The thermic element may be supported on a bracket 47 and a heat coil 48 is located on the inside of the sleeve 46. The sleeve 46 may be closed by a cap 49. The sleeve may be, if desired, suitably ventilated by means of openings that may be formed in its wall. The sleeve is also provided with a pair of binding posts 50 and 51 for connecting the device with an external circuit.

20 The heat coil 48 is connected at one end to one end of the thermic element 45 and at its central point with the binding post 50 and at its remaining end to the fixed contact 52. The thermic element is provided with a contact 53 that is adapted to make contact with, and be separated from, the fixed contact 52 by variation of the temperature of the element produced by the heat coil 48.

30 The device is connected to the system by means of the binding posts 50 and 51. The binding post 50 is connected with the battery 15 and the current from the battery divides and passes through the heat coil 48. A part 35 of the current passes through the thermic element 45 and its movable contact 53 and the other part goes direct to the fixed contact 52. The current then passes through the primary coil 10 of the induction coil 40 to the ground. When the temperature of the thermic element 45 is raised, the contacts 53 and 52 are separated and the current then passes through one-half of the resistance coil 48. Thus the resistance in the circuit, 45 as produced by the resistance coil, is doubled when the thermic element separates the contacts 52 and 53 which decreases the current flow through the primary circuit. This occurs upon the expiration of a sufficient length 50 of time to permit the ignition system to arrive at a substantially perfect operative condition.

In the form of device illustrated in Fig. 8, the thermic element 45 is so connected 55 as to open a shunt to the resistance coil 55 which is, preferably, located on the outside of the sleeve 46 and so that its temperature will not materially affect the thermic element 45. The thermic device 45 is actuated 60 by a coil 56 that is connected in series with the primary coil of the induction coil of the ignition system. The current through the primary coil 10 at all times passes through the heat coil 56 and, consequently, the thermic element 45 is at all times proportionately

affected by the current that flows through the primary coil 10.

The bracket 47, which supports the thermic element 45, is provided with a binding post 57. Also, one end of the coil 55 is connected to the binding post 58 and the other end of the coil 55 is connected to the fixed contact 52. The binding posts 57 and 58 are used for connecting the device in the primary circuit to the ignition system.

One end of the coil 55 and the anchored end of the thermic element 45 are connected to the battery 15 through the binding post 57, while the series coil 56 is connected to the primary coil 10 of the ignition system through the binding post 58. When the engine is operated for a sufficient period of time to cause the current through the coil 56 to heat the thermic element to a temperature sufficient to cause it to separate the contacts 52 and 53, the current will then pass through the coil 55 as well as the heat coil 56 which will produce sufficient heat to maintain the separation under normal operations 85 of the engine, but when the engine decreases in the quantity of current that it utilizes for any reason whatsoever, for a sufficient period of time, the temperature of the coil 56 will be decreased sufficiently to permit the 90 contacts 52 and 53 to close together and thus short circuit the coil 55 which will eliminate the resistance of the coil 55 from the circuit and give a greater quantity of current to the primary coil 10 of the ignition system. 100

I claim:

1. In an ignition system, a primary circuit, a resistance member in the primary circuit and an electric thermic element connected to the primary circuit for varying the 105 resistance according to the amount of current flowing through the primary circuit.

2. In an ignition system, a primary circuit, a heat coil connected in series in the primary circuit, and a thermic element operated by 110 the heat coil, a resistance member, the connection of the resistance member with the primary circuit controlled by the thermic element.

3. In an ignition system, a primary circuit, a resistance member, means for shunting the resistance member, an electric thermic element connected to the primary circuit, for opening and closing the said shunting means for varying the resistance of the 120 thermic circuit according to the amount of current flowing through the primary circuit.

4. In an ignition system, a primary circuit having a rheostat, and a thermic device, the thermic device heated by the current through the said circuit and operating the rheostat to vary the resistance in said circuit. 125

5. In an ignition system, a primary cir- 130

cuit having a rheostat, and a heat coil, a thermic device for operating the rheostat upon and actuated by the heat of the said coil to vary the resistance in said circuit.

6. In an ignition system, a primary circuit having a rheostat, and a heat coil, a mechanical bellows containing a gas and the

heat coil for operating the rheostat to increase the resistance in said circuit upon increase of the current quantity flowing in said circuit in a given time.

In witness whereof I have hereunto signed my name to this specification.

MARION MALLORY.
